AIR HUMIDIFIER FOR A COMBUSTION ENGINE

William G. Hardt, Chicago, Ill.

Application August 31, 1937, Serial No. 161,818

2 Claims. (Cl. 261—100)

This invention relates to an improved air humidifier for a combustion engine.

One of the main objects of this invention is to provide an improved humidifier for moistening the air as it passes from the air cleaner into the intake of the carburetor of an automobile engine.

Another object of this invention is to provide such a humidifier which is simple and inexpensive in construction, so that it can be produced 10 very economically and at the same time will be durable and reliable in use.

A further object of this invention is to provide such a humidifier which can be readily regulated to admit a larger or smaller quantity 15 of liquid to the air as it is drawn into the carburetor.

These and various other objects and advantages are attained with this invention, as will 20 become apparent from the following description, taken in connection with the accompanying drawing wherein the invention is shown in its preferred form; it being understood that various other arrangements and forms of construction may be adopted in carrying out the objects and 25 purposes of this invention.

In the drawing:

Fig. 1 is an elevational view, illustrating diagrammatically my invention as applied to the connecting conduit between the air cleaner and the carburetor of a well known automobile, with the regulating valve controllable from the automobile dash.

Fig. 2 is an enlarged view of the humidifier mounted in position in the air passage between the air cleaner and the carburetor.

Fig. 3 is a plan view of the humidifier.

Fig. 4 is an enlarged cross-sectional view thereof, taken on line 4—4 of Fig. 3.

Fig. 5 is a plan view of the fabric diaphragm.

The humidifier or air moistening device disclosed in this application is more particularly adapted for use on an automobile engine, and is especially arranged to be applied to the connecting conduit between the air cleaner and the carburetor of the automobile, so as to supply a small quantity of moisture to the air as it is drawn from the air cleaner into the carburetor. It will function automatically thru the suction of the engine, and will vary in the quantity of moisture drawn up and supplied to the air in harmony with the quantity of air drawn into the carburetor.

In the drawing the invention is illustrated in its preferred form of construction comprising a liquid container 10 which is mounted in the con-

necting portion between the air cleaner 11 and the carburetor 12, being preferably secured within a neck 13 of cleaner 11, as by means 10', and seated on the upper end of the intake tube 14 of carburetor 12, whereon said neck is mounted. 5 A short pipe or nipple 15 extends from the container thru a suitable opening in neck 13; and a fluid tank 16, provided with a gauge 17, is connected by a conduit 18 with said pipe 15. A regulating valve 19 is provided on said conduit, 10 being preferably threaded to the end of the conduit and the pipe 15, and it is adapted to be controlled from the automobile dash 20 by means of a rod 21 extending from the dash to a handle 19' on valve 19.

The container 10 is preferably arranged in the shape of an annular tube or tubular member, of copper, which has a slit 22 provided annularly around its upper part. An absorptive or permeable member 23 is mounted across the container, and it is preferably in the form of a diaphragm or sheet of fabric, of linen or else wool, stretched across the container and having its end part inserted in slit 22 to be immersed in the liquid container. The inner end part of member 25 23 may be enlarged, as by securing a rod-like element 24 in the end hem of said member, to prevent withdrawal of the end part thru the slit.

Securing means is further provided to hold the fabric member 23 in the slit, it also permits the 30 passage of the liquid therethru from the container, and this is preferably in the form of a semi-cylindrical band 25 of rubber forced into the slit at the inward side of said member 23, and a flat rubber band 26 forced into the slit 35 at the outward side of said member 23. These rubber bands hold the fabric member 23 firmly in position in the slit, and by their smooth surfaces also serve to facilitate the smooth flow of the liquid, such as water, thru the end part of 40 the fabric diaphragm, between said bands positioned in the slit, out of the container, and into the main intermediate part which is stretched across the air intake channel leading to the carburetor; and furthermore, it serves to prevent 45 the liquid from splashing out of the container.

It is apparent from the above disclosure that this humidifier is simple and economical in construction, and can be mounted in an out-of-the-way position in the connection between the carburetor and the air cleaner, and that it can be easily regulated by the control valve to admit the exact quantity of liquid desired to the air flowing to the carburetor, whereby to produce the most efficient result. This invention not only 55

produces a saving in fuel, but it also brings about an exceptionally smooth running of the engine.

I claim:

- 5 1. A humidifier for a carburetor having an air clearer on its air intake end, said humidifier consisting of an endless tubular liquid container having a continuous slit annularly around its upper portion and being mountable in the connecting portion between said cleaner and carburetor, means for conducting liquid to said container, a fabric diaphragm stretched across said container and having its end part inserted thru said slit, to conduct liquid from the container, and band means wherewith said fabric is secured 10
- 10 15 in the slit.
- 15 2. In an automobile having a carburetor with

an air intake tube also an air cleaner with a discharge tube mounted on the carburetor tube, a humidifier comprising a slitted annular tubular container mounted in said connected tubes and having liquid intake means extending beyond said connected tubes, fabric sheet means stretched across the space in the container and tubes and having its end part extending thru the slit into the container to take-up liquid therefrom, and smooth surfaced band means on the opposite 10 sides of the sheet means positioned in the slit, to secure the sheet means therein and to permit the passing of the liquid from the container thru said end part in the slit and into said sheet means. 15

WILLIAM G. HARDT.
